Specification for Design.

Patented Apr. 23, 1912.

Application filed September 25, 1911. Serial No. 651,301. Term of patent 7 years.

To all whom it may concern:

Be it known that I, FRANCIS MILLS CASE, a citizen of the United States, residing at Canton, in the county of Stark and State of Ohio, have invented a new, original, and ornamental Design for a Casing for Carpet Sweepers and Cleaners, of which the following is a specification, reference being had to the accompanying drawing, forming part thereof.

In the drawing, Figure 1 is a front-side perspective view of a casing for carpet

sweepers and cleaners embodying my invented design. Fig. 2 is a full front perspective view of the same. Fig. 3 is a side elevation of the same.

I claim:

The ornamental design for a casing for carpet sweepers and cleaners, as shown.

FRANCIS MILLS CASE.
